COKE-OVEN OPERATING APPLIANCE

Singleton H. Kimmel, Pittsburgh, Pa., assignor
to Koppers Company, a corporation of Dela-
ware

Application January 17, 1939, Serial No. 251,295

7 Claims. (Cl. 202—270)

The present invention relates to the renovating of coke-oven heating walls in general and more especially pertains to the reconditioning of such heating walls of horizontally elongated coking chambers as are adjacent or contiguous to highly heated walls in an operating battery thereof.

Occasionally there arises the necessity of repairing one or a part thereof or more heating walls of the coke ovens in a battery thereof without disturbing normal operations in closely adjacent ovens. A damaged heating wall may in some instances lie immediately adjacent another that is in excellent condition. In consequence, however, of its proximity to the damaged oven, it has been heretofore thought necessary, for the establishing of thermal conditions that are tolerable for the workmen in the coking chamber involved in the repairs, to cool the good wall, or even several of the adjacent good walls, down to a temperature where the resulting contraction is so extensive that the continuity of the brickwork is seriously disorganized and cracks, fissures and distortions appear which necessitate widespread restoration in what had previously been completely satisfactory walls, before the same can be reheated and returned to acceptably operative condition. Such circumstances as the above are especially serious in the case of silica walls because of both the complexity and of the relatively large changes in volume such material passes through at well-known points on curves representing its expansion characteristics. One of the crystalline modifications of silica present in the bricks ordinarily used in coke-oven wall construction, undergoes a sharp change in volume at temperatures as low as about 445° F. It is obvious therefore that a silica wall should be maintained at a temperature at least somewhat thereabove and preferably above about 1475° F. If more or less of its integrity is to be preserved; such degree of heat in a heating wall of course is absolutely prohibitive to a workman's entering the therewith associated coking chamber, even for a shorter period, and one of the objects of the present improvement is to provide inexpensive, simple and effective means whereby one of the heating walls of a carbonization chamber can be maintained at said relatively high temperatures and even with continued combustion in progress in all or a part of its heating flues while simultaneously providing in the opposite heating wall and in the intervening oven chamber, such temperatures as well as such available working space that workmen can enter the latter and

handle the brickwork of the damaged wall without the slightest discomfort.

Another object of invention is to provide means for the stated purpose that can be constructed by artisans of ordinary skill and which can be placed in operating position by employment of none other than the auxiliary mechanical equipment used around any coke-oven battery.

A further object of the instant improvement is obviation not only of the loss of potential plant production that is occasioned by the necessity of cooling good coke-oven heating walls to such temperatures as produce disruptive stresses therein solely for the purpose of providing conditions comfortable for workmen in an adjacent heating wall, but also of the economic loss to the wall itself that is engendered by a practice which is made inexpedient by the hereinafter described invention. The invention has for other objects such other improvements and such operative advantages or results as may be found to obtain in the processes or apparatus hereinafter described or claimed.

Briefly stated, the present invention comprises forming, outside the battery structure, rigid, mobile, heat-insulating shields of substantial yet wieldable proportions and thereafter inserting them through the mouth of that oven having a to-be-repaired and a good heating wall, and disposing a plurality of them along the face of the latter which it is planned to maintain hot. In general, it has been found expedient to form the said heat-insulating shields of invention as units comprising a heavy layer of an insulating material supported on a reinforcing framework which is about six feet in width and in length about six inches shorter than the height of the coking chamber in which they are to be employed. They should, obviously, have no dimension greater than can be conveniently passed through the mouth of the coking chamber. The said shields should be preferably about six inches shorter than the height of the to-be-protected wall in order to allow some movement in a vertical direction, for purposes hereinafter explained, and also as an aid toward facilitating their movement and adjustment along the heating-wall face. When of the stated dimensions, they are adapted for easy handling by a light crane and are slidable along the oven sole and the face of the heating wall by means of the ram of the pusher-machine. It is of course desirable so to proportion the width of the shields that only entire units will be required completely to insulate a heating wall. A better appreciation of the inexpensiveness of the heat shields of invention, of their ease of installa-

tion, and of their effectiveness, for the stated purpose, will be obtained from a description of their methods of manufacture and installation made with the assistance of the accompanying drawings.

5 In the accompanying drawings forming a part of this specification and showing for purposes of exemplification a preferred apparatus and method in which the invention may be embodied and practised but without limiting the claimed invention specifically to such illustrative instance or instances:

10 Fig. 1 is a vertical view in elevation of a form of heat-insulating-shield made according to provisions of the present invention;

15 Fig. 2 is a side view in elevation of Fig. 1;

20 Fig. 3 is a horizontal section taken along the line III—III of Fig. 1;

25 Fig. 4 is a vertical section taken longitudinally through a diagrammatically represented horizontally elongated coking chamber and showing a heating wall partially covered by the heat-insulating shields provided by the present improvement, and also the manner in which the ram of the pushing machine is employed to spot them at the desired point along the heating-wall face;

30 Fig. 5 is a vertical section taken longitudinally of a battery of horizontally elongated coking chambers and showing opposite walls of two adjacent coking chambers as covered by heat-insulating shields of the invention, the masonry of the intermediate flued heating wall, up to a point adjacent the horizontal duct, having been entirely removed for purposes of rebuilding, and the masonry of the upper part of said removed heating wall having been suspended by rods that extend downwardly from the top of the battery through the inspection holes of the heating flues and tie into metal plates that cover the bottom of the unremoved tiers of masonry; and

35 40 Fig. 6 is a perspective view, parts in section, of the upper part of a coke-oven battery of that type having a gas-flow system in which the heating flues at one battery side are all operative simultaneously as either flame-flues or combustion-products flues alternately with those on the other battery side, and showing a part of one heating wall removed for its rebuilding and with the heating flues of the remaining part of the heating wall communicably connected by means of a temporary combustion-products duct with the horizontal duct of an adjacent heating wall, that section of the coking chamber contiguous to said remaining heating-wall part being isolated behind a transverse insulating bulkhead and that section of the good heating wall opposite the removed heating flues being covered by the heat-insulating shields provided by the invention, such an arrangement making repairs on a partial heating wall conveniently possible while maintaining the opposite partial wall at temperatures above those at which disruptive stresses will develop therein, as will be hereinafter described.

45 The same characters of reference designate the same parts in each of the views of the drawings.

50 55 Referring now to the drawings, and particularly to Figs. 1, 2, 3, in which there is shown a suitable form of mobile heat-insulating shield whereby the heating wall of a coking chamber, that is directly opposite one which is destined for cooling and extensive rebuilding, can be so insulated against radiation of heat therefrom that temperatures of 1400–1600° F. can be maintained therein by continuance of the combustion of fuel gas in its heating flues and without giving rise to 60 65 70 75 uncomfortable conditions for workmen in the

adjacent coking chamber, the insulating-shield 10 may be conveniently and cheaply formed from lengths of angle-iron, or the like, that is of appropriate dimensions for easy handling. It has been demonstrated in practice that said shields can be easily shifted and installed with equipment ordinarily available in a coke-plant if their width 11 is about six feet and their height 12 about six inches less than that of the height of the to-be-repaired coking chamber, or at least no greater than will conveniently pass through the mouth 13 of the involved coking chamber.

5 10 15 After cutting the angle-iron stock into lengths conforming to such dimensions, the ends thereof may be welded together to form the rectilinear framework shown in Fig. 1, the peripheral members being supported by struts 14 in any preferred arrangement, but that however shown in the said Fig. 1 has proven satisfactory. To the upper stretcher of the frame is welded a lifting eye 15, whereby the shield is supportable on a crane for purposes of conveyance, and also a spring-member 16 that protrudes sufficiently, from said stretcher, to span the to-be-repaired oven and to rigidly support the shield against the wall that is to be insulated, by its pressure against the upper part of the opposite wall.

20 25 30 35 40 45 50 55 60 Across the welded framework, formed from the sections of angle-iron, there is stretched and thereto attached, some such perforate reenforcing material 17 as woven-wire, expanded metal, or the like, capable of supporting a heavy layer of insulating material. This reenforcing material is thereafter covered with a coating 18 of a material having good insulating properties, said coating being preferably about three inches in thickness. The coating has been satisfactorily formed of a cement compounded of five parts of C-3 Silocel, one part fire clay and one part Lumnite cement, all mixed to form a workable mixture which is then applied over the reenforcing material 17 of the shield-frame. After this cement has hardened, the heat-insulating shield is ready for placing in operating position against the hot brickwork of the good wall that is to be protected. The framework of the insulating shields is not necessarily limited to a filling with an insulating material formed from a compound that is cast or molded onto the perforate reenforcing material because it is obvious that a similarly effective shield may be built up by filling the shield-frame with pre-formed blocks or fitted sections of non-plastic material. The insulating cement may also be successfully compounded from other cellular constituents having heat-insulating properties, such, for example, as calcined diatomaceous earth, exfoliated vermiculite, refuse from the manufacture of insulating bricks or the product Haydite which is a bloated shale, or any other material of similar properties.

65 70 75 80 85 90 The vertical edges 19 of the heat-shields may be formed as surfaces that lie in a single plane, as illustrated in Figs. 2, 3, or they may be so designed that adjacent shields will dove-tail together in tongue-and-groove fashion, in interest of better heat confinement; however, the former type has proven satisfactory in practice.

95 The mobile heat-insulating shields for coke-oven walls that the present invention provides can be installed in the coking chambers and be held closely against the to-be-insulated walls in a very simple manner. They are adapted to be easily slideable along the face of a heating wall by the ram of the coke-pusher machine and, in consequence of this fact, they can be installed in

operating position in a hot coking chamber and removed therefrom without greatly reducing its temperature or requiring a workman's entering an oven at relatively high temperature, or exposing him in any degree to the rigors of excessively high temperatures. The large surface covered by each unit makes it possible completely to cover an entire heating wall in a relatively short time. The most of these advantages result from the facts that the shields are prepared outside the battery structure and that they are mechanically installable and removable therefrom.

Let it now be assumed that in a battery of horizontally elongated coke ovens the heating walls of which are all at customary operating temperatures, it becomes desirable to re-build an entire flued heating wall, without cooling the opposite heating walls of thereto adjacent coking chambers below a temperature at which an extensive contraction of their brickwork will take place, while also maintaining in the to-be-repaired wall temperature conditions that are comfortable to the workmen. An oven door is removed from the coke- or the pusher-side of the two ovens 20 (Fig. 5) having the common heating-wall that it is contemplated repairing. Channel-irons 21 of sufficient width to slideably receive the lower edges of the heat-insulating shields and of sufficient length to extend from face-to-face of the 30 battery are then slid along the soles of the two adjacent ovens and adjusted into positions close to the lower edge of each of the heating walls 22 that are opposite to the to-be-repaired wall and which are to be maintained hot during the repair period. These channel-irons serve both as a support for the lower edges of the insulating shields and also as a guide or trackway for sliding them into position along the oven walls it is desired to insulate.

10 The already prepared heat-shields 10 are then attached to a crane, or the like, by means of the lifting eye 15 and elevated to such position that their lower edges are slightly above the soles of the coking chambers at the pusher side of the battery. A lower corner of each shield is then inserted between the vertical walls of the channel-irons and the whole shield is forced into the oven by pushing it along the channel-iron by means of the coke-ram 23 of the pusher-machine, as shown in Fig. 4. This operation is repeated until the two oven-heating walls opposite the to-be-repaired heating wall are entirely covered from the coke- to pusher-side of the battery. The heat-shields are supported closely against the hot walls at their lower edges by means of the channel-irons and at their tops by the pressure of spring-member 16 against the top of the wall that is to be dismantled. After the contiguous good heating walls have been thus covered with an easily installable and removable layer of heat-insulating material, if not previously so done, the fuel-gas supply to the heating wall which it is contemplated dismantling, is turned off for purposes of cooling while at the same time the quantity of fuel-gas delivered to the insulated, good walls may be reduced until a preferred temperature in their brickwork has been reached. It has been determined in practice that in the case of good oven walls formed from silica bricks, maintaining them at temperatures of 1400-1600° F. is adequately high to obviate development of cracks, distortions and the like, that require extensive pointing-up when such temperatures are accompanied by judicious adjustment of the pressure of the buckstays against the wall.

The layer of heat-insulating material provided by the above-described heat-shields is adequate to prevent the flowing of a significant quantity of heat from the insulated good walls into the adjacent coking chambers 20, and the to-be-repaired 5 wall will therefore soon cool to a temperature where its brickwork can be easily handled and dismantling thereof can proceed, the temperatures in the adjacent coking chambers themselves being also such that they can be entered. 10 by workmen without the slightest discomfort.

In Fig. 5 there is shown a coke-oven battery in which the greater part of a flued heating wall that is common to two coking chambers has been removed for rebuilding, the opposite heating walls 15 of the adjacent coking chambers being insulated in accordance with provisions of the present invention. In the illustrated battery, the upper part of the brickwork of the to-be-repaired wall, including the horizontal duct 24, was in good 20 condition and did not need substitution. This section of the wall was therefore retained in the battery during repairs and has been suspended from supporting angle-irons 25 (see Fig. 6) that are disposed along the top of the battery, by 25 means of tie-rods 26 and metal plates 27, said tie-rods being inserted through the flue-inspection holes 28 found in any coke-oven structure. The said angle-irons 25 also serve to distribute the weight of the retained wall-portion over a large 30 area; it is obvious that they must be of such dimensions and in such arrangement as not to interfere with normal functioning of the larry-car which is used to charge other ovens of the 35 battery.

As clearly shown in Fig. 5, the retained upper sections of the dismantled wall are employed as supports against which the spring-members 16 of the heat-shields 18 can press to hold the latter closely adjacent the insulated wall. In many 40 cases of wall repair, these upper wall-sections will be available for such purpose because they are frequently still in satisfactory conditions when the lower brickwork requires rebuilding. When, however, an entire heating wall must be dismantled, it is clear that some other appropriate 45 means must be furnished to support the upper parts of the heat-shields. In as much as in the case of complete-wall dismantling, the oven roofs will be removed, the said shields can be supported 50 by tying them to permanent fixtures along the top of the battery, according to the best imagination of the superintendent of repairs.

After completion of the wall repairs, the heat-shields may be slideably removed from in front of 55 the insulated wall by the coke-pusher ram in much the same manner as they were installed and, in many instances, they are re-usable.

In some circumstances, there may arise the necessity of rebuilding only a portion of a heating 60 wall. As shown in the accompanying Fig. 6, that portion of a coking chamber which is in satisfactory condition may be walled off from its damaged part by means of a temporary crosswise bulkhead 29 that may be built up in situ of insulating bricks or preformed outside the battery and slid into place along the oven sole. In said Fig. 6, the illustrated bulkhead 29 is of the latter type having been supplied with skids 38 upon which it was slid into place by the ram of the 70 pusher machine. That section of a good heating wall opposite the to-be-repaired wall-section can then be insulated and retained hot by means of that number of heat-shields of the present invention appropriate to cover the same. In the 75

case shown in said Fig. 6, the channel-iron 21, which extends only half the distance crosswise of the battery, assists in the support of two of the heat-shields of invention, and the damaged portions of the opposite wall have been removed from a level adjacent the horizontal duct 24 down to the level of the gas and air ports respectively 30, 31. With such an arrangement, fuel gas can be burned in all of the heating flues of heating wall 10 32 and also in those remaining heating flues of heating wall 33 which are adjacent that portion of the intermediate coking chamber isolated behind bulkhead 29.

In proceeding with repairs on only a fraction of 15 the total number of heating flues comprising a heating wall while simultaneously burning fuel gas in the remainder thereof, it will sometimes be necessary to make special temporary provision to remove combustion-products from those flues 20 that are still being heated. The nature of such provision will depend upon the extent of the wall repairs and also upon the scheme of flow of fuel gas and combustion-products along the wall and through the regenerators of that particular type 25 of oven being reconditioned. In some instances it will be necessary temporarily to tie an auxiliary duct between the upper ends, or the horizontal duct, of the still heated flues and a convenient point of entry into the heating system, for example the horizontal ducts, of a thereadjoining heating wall. This is preferably carried out in such manner that the gas-flow reversing mechanism for the battery can be utilized as normally 30 to direct gaseous flow through those flues of a to-be-repaired heating wall in which combustion is continued. In the battery illustrated in Fig. 6, the flow of gases in any one heating wall is normally such that those heating flues of a wall on one side of the battery median alternate 35 with those on the other side in being flame flues and combustion-product flues, thus those flues at one side of the battery intermittently function to carry away combustion-products from the other battery-side. In the repair problem presented in Fig. 6, the required reconditioning of heating wall 33 was so extensive as to necessitate complete removal and rebuilding of those flues which would normally function to carry away 40 combustion-products from those that are to be retained hot during the period of reconstruction. Consequently, some other provision must be provided to conduct their waste gases to the stack. To satisfy this requirement, the temporary auxiliary duct 34 was installed on the battery deck 45 and arranged to communicably connect an inspection hole 28 of each of the heating walls 32, 33. Normal communication between the extant heating flues of wall 33 and the to-be-repaired flues thereof has been interrupted by installation 50 of a temporary barrier-wall 35 in the associated horizontal duct 24. These simple expediencies therefore form of said extant flues of wall 33 a temporarily separately heatable unit. During 55 that part of a regenerative heating cycle in which they are functioning as flame-flues, their combustion-products flow by means of temporary duct 34 into the horizontal duct for heating wall 32, and are so disposed of, and during the period of reverse flow in the heating cycle, combustion- 60 products will be withdrawn from the horizontal flue of their opposite heating wall and down through their own underlying regenerators to reheat the latter; i. e., in the illustrated arrangement, the regenerators beneath the yet operative flues of wall 33 will be heated by waste- 65

heat from wall 32. Instead of being formed of continuous construction, bulkhead 29 contains preferably a plurality of port-holes 36 that are each closed by an easily extractable brick 37, each such port is thus optionally serviceable for the purpose of controlling a gradual flow of heat from an already heated portion of a coking chamber into a newly reconstructed part; a feature that assists in the slow drying of the latter and its gradual return to operating temperatures. 70

In some applications of the instant improvement, such for example, as those in which the heating walls are heated with rich gas distributed into the lower parts of the heating flues from rich-gas conduits or gun-bricks that extend crosswise of a battery in the upper parts of the regenerator walls, that occasion may arise in which, during the repair interval, it is desirable to deliver rich gas to heating flues which, in respect of said conduit, are downstream of those flues being reconditioned and therefore employing no fuel gas. In such circumstance it has been found convenient to extend an auxiliary pipe from the reversing valve of the rich-gas main, at the face of the battery, inwardly through said gun-brick to a point beyond the damaged flues where the same is sealed into the gun-brick by an easily extractable granular or fibrous packing material, thus the normal rich-gas reversing mechanism can still be employed to regulate flow of fuel gas in that portion of the flues of the to-be-repaired wall in which heating is to be continued. 75

Upon occasion, during the repairing of coke-oven heating walls by the above described means it has been found advisable to rebuild some of the regenerator walls therebeneath while maintaining at high temperatures those regenerators associated with the still heated coking-chamber walls adjacent the to-be-repaired coking-chamber walls. This circumstance has necessitated the provision of means whereby the brickwork of a regenerator wall immediately adjacent a wall undergoing repairs can be so well insulated that a damaging degree of its contraction cannot take place and will, in addition, also provide comfortable conditions for the workmen. For this purpose, two thicknesses of asbestos fabric depending as a curtain from the brickwork of the sole of the to-be-repaired oven and down to the battery-supporting mat, have been employed with highly satisfactory results for the workmen and also for the brickwork itself. 80

As hereinbefore mentioned the heat-shields of invention are preferably made about six inches less in length than the height of the coking chamber in which they are to be employed. This feature offers the advantage that the individual sections can be easily raised somewhat above the level of the oven sole thereby making that part of the coking chamber accessible to the installation of new bricks, wherever necessary. 85

By means of the herein-described improvement, it now becomes possible to apply over the entire surface of a hot coke-oven heating wall 65 and to remove therefrom, without at any time subjecting the workmen to disagreeably high temperatures, a heat-insulating sheathing that is adequate to permit a relatively high rate of combustion being continued in the insulated wall 70 while, in an immediately adjacent cooled wall and in the intermediate coking chamber, such moderate temperatures will prevail that workmen can enter the said intermediate coking chamber and remove and reconstruct the brick- 75

work of the cooled wall without being subjected in any degree to enervating temperatures.

The following description of a specific application of the improvement provided by the invention will give a clearer picture of the effectiveness of the method, its utility and advantages. In a coke-oven battery, the heating flues of which were maintained on the chamber side at operating temperatures of about 2000° F., it became advisable to renovate an entire heating wall, formed of silica bricks, in some manner that would cause a minimum of disturbance to the masonry of the heating walls there-adjacent and a minimum loss of capacity in plant-production. For the two surfaces of both heating walls that were contiguous to the to-be-repaired wall, heat-shields were made according to the hereinabove-given specific description. The coking chambers, that were common to the to-be-repaired wall, had their temperatures reduced to substantially 1600° F. by lowering the quantity of fuel gas distributed to their heating walls, whereupon the heat-shields were inserted in the coking chambers and slid therealong by the ram of the pusher machine until the entire surfaces of those heating walls immediately adjacent the to-be-repaired wall were insulated by the heat-shields of invention (Fig. 5). Fuel-gas supply to the to-be-repaired wall was then cut-off and the supply of such gas to the heating walls on either side thereof somewhat reduced until the temperatures in the brickwork adjacent the heat-shields were substantially 1500° F. The doors of the coking chambers on either side of said to-be-repaired heating wall were removed and in five days the temperatures in the said carbonization chambers had been reduced to 90-100° F. without forced ventilation. At the same time the temperatures in the masonry of the adjacent insulated walls was 1500° F. The exterior surfaces of the heat-shields themselves were about 210° F. but natural draft through the coking chambers was adequate to hold the average temperature in the coking chambers at about 100° F. and even on a hot summer day the temperature therein did not rise above 110° F. After renovation had been completed, the heat-shields were pushed out of the ovens by the pusher-machine ram and the temperatures in the renovated wall and its two adjacent walls were then returned to operating temperatures without any apparent damage to the contiguous walls. During the entire repair period, the coking chambers (X in Fig. 5) next adjacent those having the insulated walls were in continuous normal operation.

It will be noted that in the above-given application of the invention, the temperature in the coking chambers was somewhat reduced from that obtaining at normal operating temperatures, before the heat shields of invention were introduced thereinto. As the technology of metals advances to furnish metals more resistant to heat, heat-shields can be provided that will make possible their insertion into coke ovens while they are at full operating temperatures.

An important advantage of the invention resides in the fact that heat-shields thereby provided can be handled and installed by mechanisms necessary to any coke-oven plant, their feature of easy mobility being conducive to their facile and rapid installation in and removal from operating position in highly heated coking chambers. By means of the invention it is possible to preform the insulating shields outside the battery structure, at normal atmospheric temperatures,

rather than building them up in situ along an incandescent heating-wall face, which for obvious reasons would be an exceedingly expensive, if not, impractical task. They are installable without cooling a good heating wall to a point approaching temperatures at which impairment thereof would begin to develop; they have been especially devised to avoid such contingency.

The pre-formed heat-shields provided by the instant improvement are adapted to be inserted mechanically into a coking chamber that is not greatly below full operating temperature and to be moved therealong to a desired point of the heating-wall face without any preparatory drastic reduction of its temperature being required; they can be similarly removed intact for further use.

Advantages of the present invention are realizable not only in its above-described applications, where it is desired to replace the masonry of a whole or a partial heating wall but, by reason of their utility in temporarily establishing a steep temperature gradient between opposite walls of an operating coking chamber, the heat-shields are of great service in circumstances where less extensive renovation is contemplated. During the operation of a coke oven, the occasion may arise, for example, in which it is merely necessary to renew the joints or patch small areas in the existing brickwork of a heating wall by introducing new mortar thereinto. The performance of such task is greatly facilitated by use of the herein-described heat-shields which enable the operator temporarily to reduce the temperature of that section of the coking chamber immediately adjacent the to-be-patched wall sufficiently that much of the original water content of the mortar and consequently its plasticity can be preserved as it is flowed through said heated oven section to the point of its application, thereby providing improved distribution and deeper penetration of the mortar into the hot brick-work. This reduction in temperature also helps preserve the integrity of the conduits employed for flowing the mortar to the points of application.

The invention as hereinabove set forth is embodied in particular form and manner but may be variously embodied within the scope of the claims hereinafter made.

I claim:

1. In combination with a coke-oven battery having a carbonization chamber and laterally disposed thereof a flued heating wall adapted to be maintained at an elevated temperature, means for retaining said heating wall at higher temperatures while cooling a thereto adjacent heating wall, said means comprising: mobile and substantially self-supportable heat-shields that are pre-formed outside the carbonization chamber and are insertable and removable through a mouth thereof, said heat-shields comprising: a body of refractory, heat-insulating material of adequate thickness and sufficient surface to prevent significant heat transfer from the substantial portion of the heating-wall surface that it is disposed to cover; and, for the so-formed heat-insulating material, a securing structure capable of preventing significant deformation thereof during handling.

2. In combination with a coke-oven battery having a carbonization chamber and laterally disposed thereof a flued heating wall that is adapted for heating to an elevated temperature, means for retaining said heating wall at higher temperatures while cooler temperatures exist in

- a thereto adjacent heating wall, said means comprising: mobile and substantially self-supportable heat-shields that are pre-formed outside the carbonization chamber and are adapted both for passing through the mouth thereof and for movement, along the surface of the said wall that is adapted to be heated, by such means as the ram of the coke-pusher machine, said heat-shields comprising: a body of refractory, heat-insulating material formed with adequate thickness and sufficient surface to prevent significant heat transfer from a substantial portion of the face of the heating wall that is adapted for heating to elevated temperature; and, for the so-formed heat-insulating material, a securing structure adapted to resist significant deformation thereof when it is moved through the heated carbonization chamber by pressure of such device as the coke-pusher ram.
10. In a coke-oven battery having a carbonization chamber and laterally disposed thereof a flued heating wall, the combination of: means adapted for heating said flued heating wall to elevated temperatures; and other means for preventing undue transfer of heat therefrom into an adjacent heating wall and a carbonization chamber therebetween, so that space of said chamber and the masonry of said adjacent heating wall can be held at temperatures convenient for workmen engaged in their renovation even though the heating wall that is adapted for heating is at elevated temperatures, said other means comprising: a pre-formed heat-insulating shield having a surface that substantially conforms to a large section of the heating wall which is disposed for heating, said shield being adapted for passing through a mouth of the carbonization chamber and for movement along the face of said heating wall without substantial deformation, and comprising: a mass of refractory heat-insulating material comprising a bonded cellular constituent that is formed in adequate thickness and with sufficient surface to impede substantial transfer of heat from a larger section of the face of that heating wall that is arranged for heating to elevated temperatures; and for the so-formed refractory material a securing structure adapted to obviate any considerable deformation thereof when the same is moved along the face of the to-be-insulated heating wall by appropriate means, such as the ram of the coke-pusher machine.
3. In a coke-oven battery having a carbonization chamber and laterally disposed thereof a flued heating wall, the combination of: a flued heating wall that is adapted to be maintained at elevated temperatures; and, disposable along the face of said heating wall when the same is at elevated temperatures, substantially rigid and pre-formed heat-insulating shields that are adapted for insertion in the carbonization chamber and for removal therefrom without substantial deformation, said shields comprising: a body of refractory, heat-insulating material formed in adequate thickness and with sufficient thereto conformable surface to obviate substantial transfer of heat from the heating wall at elevated temperatures.
5. In combination with a coke-oven battery, the combination of: a carbonization chamber; a flued heating wall there-adjacent that is adapted for heating to elevated temperatures; a guideway that is removably disposable in said carbonization chamber to support and facilitate movement along the face of said heating wall of heat-insulating shields arranged to obviate substantial transfer of heat therefrom, so that said heating wall can be maintained at elevated temperatures even though an adjacent carbonization chamber and heating wall are at temperatures comfortable for workmen; and heat-shields that comprise refractory heat-insulating material and are adapted to cover a substantial part of said heating-wall face and for movement along said guideway without substantial deformation.
10. In combination with a coke-oven battery, the combination of: a carbonization chamber; a flued heating wall there-adjacent that is adapted for heating to elevated temperatures; a guideway that is removably disposable in said carbonization chamber to support and facilitate movement along the face of said heating wall of heat-insulating shields arranged to obviate substantial transfer of heat therefrom, so that said heating wall can be maintained at elevated temperatures comfortable for workmen; and heat-shields that comprise refractory heat-insulating material and are adapted to cover a substantial part of said heating-wall face and for movement along said guideway without substantial deformation.
15. In combination with a coke-oven battery, the combination of: a carbonization chamber; a flued heating wall there-adjacent that is adapted for heating to elevated temperatures; a guideway that is removably disposable in said carbonization chamber to support and facilitate movement along the face of said heating wall of heat-insulating shields arranged to obviate substantial transfer of heat therefrom, so that said heating wall can be maintained at elevated temperatures comfortable for workmen; and heat-shields that comprise refractory heat-insulating material and are adapted to cover a substantial part of said heating-wall face and for movement along said guideway without substantial deformation.
20. In combination with a coke-oven battery, the combination of: a carbonization chamber; a flued heating wall there-adjacent that is adapted for heating to elevated temperatures; a guideway that is removably disposable in said carbonization chamber to support and facilitate movement along the face of said heating wall of heat-insulating shields arranged to obviate substantial transfer of heat therefrom, so that said heating wall can be maintained at elevated temperatures comfortable for workmen; and heat-shields that comprise refractory heat-insulating material and are adapted to cover a substantial part of said heating-wall face and for movement along said guideway without substantial deformation.
25. In combination with a coke-oven battery, the combination of: a carbonization chamber; a flued heating wall there-adjacent that is adapted for heating to elevated temperatures; a guideway that is removably disposable in said carbonization chamber to support and facilitate movement along the face of said heating wall of heat-insulating shields arranged to obviate substantial transfer of heat therefrom, so that said heating wall can be maintained at elevated temperatures comfortable for workmen; and heat-shields that comprise refractory heat-insulating material and are adapted to cover a substantial part of said heating-wall face and for movement along said guideway without substantial deformation.
30. In combination with a coke-oven battery, the combination of: a carbonization chamber; a flued heating wall there-adjacent that is adapted for heating to elevated temperatures; a guideway that is removably disposable in said carbonization chamber to support and facilitate movement along the face of said heating wall of heat-insulating shields arranged to obviate substantial transfer of heat therefrom, so that said heating wall can be maintained at elevated temperatures comfortable for workmen; and heat-shields that comprise refractory heat-insulating material and are adapted to cover a substantial part of said heating-wall face and for movement along said guideway without substantial deformation.
35. In combination with a coke-oven battery, the combination of: a carbonization chamber; a flued heating wall there-adjacent that is adapted for heating to elevated temperatures; a guideway that is removably disposable in said carbonization chamber to support and facilitate movement along the face of said heating wall of heat-insulating shields arranged to obviate substantial transfer of heat therefrom, so that said heating wall can be maintained at elevated temperatures comfortable for workmen; and heat-shields that comprise refractory heat-insulating material and are adapted to cover a substantial part of said heating-wall face and for movement along said guideway without substantial deformation.
40. In combination with a coke-oven battery, the combination of: a carbonization chamber; a flued heating wall there-adjacent that is adapted for heating to elevated temperatures; a guideway that is removably disposable in said carbonization chamber to support and facilitate movement along the face of said heating wall of heat-insulating shields arranged to obviate substantial transfer of heat therefrom, so that said heating wall can be maintained at elevated temperatures comfortable for workmen; and heat-shields that comprise refractory heat-insulating material and are adapted to cover a substantial part of said heating-wall face and for movement along said guideway without substantial deformation.
45. In combination with a coke-oven battery, the combination of: a carbonization chamber; a flued heating wall there-adjacent that is adapted for heating to elevated temperatures; a guideway that is removably disposable in said carbonization chamber to support and facilitate movement along the face of said heating wall of heat-insulating shields arranged to obviate substantial transfer of heat therefrom, so that said heating wall can be maintained at elevated temperatures comfortable for workmen; and heat-shields that comprise refractory heat-insulating material and are adapted to cover a substantial part of said heating-wall face and for movement along said guideway without substantial deformation.
50. In combination with a coke-oven battery having a horizontally-elongated coking oven formed between flued heating walls and, in said coking oven, a shiftable bulkhead that is removable through the mouth thereof and which comprises a mobile, pre-formed and substantially rigid slab-like member formed of a refractory heat-insulating material, whereby mutual heat transfer between larger surfaces of opposite heating walls can be optionally and extensively inhibited to establish a steep temperature gradient therebetween.
55. In combination with a coke-oven battery having a horizontally-elongated coking oven formed between flued heating walls and, in said coking oven, a shiftable bulkhead that is removable through the mouth thereof and which comprises a mobile, pre-formed and substantially rigid slab-like member formed of a refractory heat-insulating material, whereby mutual heat transfer between larger surfaces of opposite heating walls can be optionally and extensively inhibited to establish a steep temperature gradient therebetween.

SINGLETON H. KIMMEL.
